TRIVET HOT PLATE

Edward V. Platt, Manitowoc, Wis., assignor to
Paragon Electric Company, Two Rivers, Wis.,
a corporation of Wisconsin

Application August 24, 1953, Serial No. 26,554

Term of patent 14 years

(Cl. D81—10)

To all whom it may concern:

Be it known that I, Edward V. Platt, a citizen of the United States of America, residing at Manitowoc, in the county of Manitowoc and State of Wisconsin, have invented a new, original, and ornamental Design for a Trivet Hot Plate, of which the following is a specification, reference being had to the accompanying drawing, forming part hereof.

In the drawing:

Fig. 1 is a perspective view of a trivet hot plate embodying my new design.

Fig. 2 is a bottom plan view of the trivet hot plate shown in Fig. 1; and

Fig. 3 is a side elevational view of the trivet hot plate shown in Fig. 1.

I claim:

The ornamental design for a trivet hot plate, as shown.
